UNITED STATES PATENT OFFICE

JOHN M. YOUNG, OF BROOKLYN, NEW YORK, ASSIGNOR TO AMERICAN CAN COMPANY, OF NEW YORK, N. Y., A CORPORATION OF NEW JERSEY

CONTAINER

Application filed December 4, 1924. Serial No. 753,764.

My present invention relates to cans and has for a principal object the provision of an improved hinge construction, which, though particularly adapted to the interior collar tearing strip type of can, may also be usable in other adaptations and embodiments.

The invention has particular advantages in connection with tobacco cans of the flattened or pocket type, since it is desirable that the tobacco be kept from drying out during storage and shipment, which may best be accomplished by a hermetic closure, and yet a hinge closure is best adapted to the conditions of use of the package after it is received by the consumer, inasmuch as it must be opened and closed many times while the contents are being used. I, therefore, employ a tearing strip in conjunction with an interior collar member and a hinging device, in which my invention is embodied, so that the can may be hermetically sealed until the tearing strip is removed, after which it becomes a hinge cover can usable in the ordinary manner.

An important object of the invention is the provision of a hinging device which is adapted to be applied to the container with especial facility and which is highly efficient in action, as well as inexpensive to manufacture.

Numerous other objects and advantages of the invention will be apparent as it is better understood from the following description, which, taken in connection with the accompanying drawings, discloses a preferred embodiment thereof.

In the drawings, I have shown, for illustrative purposes only, a preferred form of my invention, in which—

Figure 1 is a perspective view of a tobacco can in which my invention is embodied;

Fig. 2 is an enlarged vertical section through the upper part of the container, showing clearly the hinge construction; and

Fig. 3 is a partial perspective view with the hinge parts partially broken away to better illustrate the scoring of the body.

Referring to the drawings more in detail, the reference character 11 indicates a container body, of the usual flattened form employed for tobacco. The permanent bottom end 12 is secured to said body in the usual

manner and in the present instance a permanent top 13 is secured in place by means of a seam 14, so that the container is hermetically sealed after it is packed and the contents protected from drying out, as might occur if the usual loose hinge cover were employed. The upper part of the body is scored upon lines 15 and 16 to set off a tearing strip 17, which terminates in a tongue 18 engageable by a key to tear away the strip when it is desired to open the container.

A collar member 19 is disposed within the body and extends from beneath the lowermost score line 15 above the uppermost score line 16 and is preferably curled at its upper end, as indicated at 21.

The hinge, as shown, is applied to the exterior of the container within a depression 22 in the container wall and consists of a lower part 23 spot welded at 24 to the body wall, an upper part 25 spot welded at 26 to said wall above the upper score line 16 and a pintle 27 disposed through oppositely bent hinge lugs 28 and 29, provided respectively upon said lower and upper hinge parts. The pintle 27 is preferably disposed substantially at the upper score line 16 and the lower line 15 extends diagonally into the upper line at 31 at the side of the hinge member opposite the tongue 18 of the tearing strip which projects from the side seam 32 of the can.

It will now be evident that when the tearing strip 17 is removed, the portion of the body beneath the hinge is not severed and stock is thus provided for attachment of the lower hinge part adjacent the upper score line, which latter extends across the depressed part 22 of the container wall so that said wall will be severed when the top is opened upon the hinge.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment of the invention.

I claim:

1. A can, comprising a body having a tearing strip beneath the top thereof, and a hinge consisting of a piece different from the metal of the body and applied to the exterior of the can body and connected with the body above the line of the tearing strip, and also below the line of the tearing strip, the body having a continuous one-piece wall including said tearing strip as an integral part.
2. A can, comprising a body having a tearing strip extending partially thereabout beneath the top, and a hinge having a pintle and secured to said body between the ends of the tearing strip.
3. A can, comprising a body having a tearing strip extending partially thereabout beneath the top and formed by upper and lower score lines, the upper score line extending continuously about the body, and a hinge disposed between the ends of the tearing strip and having a pintle substantially in alignment with the upper score line.
4. A can, comprising a body having a tearing strip extending partially thereabout beneath the top and formed by upper and lower score lines, the upper score line extending continuously about the body, and a hinge disposed on the exterior of the container between the ends of the tearing strip and having a pintle substantially in alignment with the upper score line.
5. A can, comprising a body having a tearing strip beneath the top thereof and a depressed panel on the exterior in the circumferential line of and interrupting said tearing strip, and a hinge consisting of a piece different from the metal of the body and disposed in said depressed panel for hingedly connecting and spacing apart the portion of the body above the tearing strip and the part below the tearing strip after said tearing strip is removed.
6. A can, comprising a body having score lines, one of which extends entirely around the body and the other of which extends partially around said body and thence into said first-mentioned score line, and a hinge disposed outside of the tearing strip set off by said score lines.
7. A can, comprising a body provided with score lines setting off a tearing strip beneath the top thereof, said score lines being arranged to sever said strip before it tears completely around the body, and a hinge applied to the exterior of the body between the ends of the tearing strip.
8. A can, comprising a body provided with score lines setting off a tearing strip beneath the top thereof, said score lines being arranged to sever said strip before it tears completely around the body, and a hinge applied to the exterior of the body between the ends of the tearing strip, said hinge comprising upper and lower members spot welded to the
9. A can, comprising a body provided with score lines setting off a tearing strip beneath the top thereof, said score lines being arranged to sever said strip before it tears completely around the body and one of said score lines extending continuously around the body, and a hinge pivoting on an axis near the last mentioned upper score line.
10. A can, comprising a body provided with upper and lower score lines setting off a tearing strip beneath the top thereof, said score lines being arranged to sever said strip before it tears completely around the body and one of said score lines extending continuously around the body, and a hinge pivoting substantially upon said upper score line, said hinge comprising upper and lower members spot welded to the body respectively above and below said upper score line and a pintle connecting said members.
11. A can, comprising a body provided with upper and lower score lines setting off a tearing strip beneath the top thereof, said score lines being arranged to sever said strip before it tears completely around the body and one of said score lines extending continuously around the body, and a hinge pivoting substantially upon said upper score line, said hinge comprising upper and lower members spot welded to the body respectively above and below said upper score line and a pintle connecting said members, the lower member being disposed substantially in the plane of the tearing strip.
12. A can, comprising a body provided with score lines setting off a tearing strip beneath the top thereof, said score lines being arranged to sever said strip before it tears completely around the body, and separate hinging means having a pintle disposed between the ends of the tearing strip and connecting the portion of the body above said strip with the remainder.
13. A hinge-top can formed with a tearing strip made in one piece with the body, combined with a continuous collar element within the body and extending past the tearing strip, and a hinge element formed of a separate piece attached to the body at points outside of the area of the tearing lines so as to hinge the body to the movable top which is produced by the removal of the tearing strip, the body having a depressed panel substantially in line with the tearing strip and the hinge element being seated in said panel.

JOHN M. YOUNG.
